AUTOMATIC CAM GRINDING MACHINE

Herbert A. Silven, Worcester, Mass., assignor to
Norton Company, Worcester, Mass., a corpora-
tion of Massachusetts

Application June 2, 1938, Serial No. 211,324

15 Claims. (Cl. 51—101)

This invention relates to grinding machines, and more particularly to an automatic camshaft grinding machine.

One object of the invention is to provide a simple and thoroughly practical machine for automatically grinding a plurality of cam blanks on an integral camshaft. A further object of the invention is to provide an automatic cycle control mechanism for controlling the relative transverse movement of the cam blank and grinding wheel, and the positioning movement of the work table to grind successive cam blanks automatically to a predetermined size and contour. A further object of the invention is to provide an automatic cycle control mechanism in which a main control valve is actuated in timed relation with the relative transverse feeding movement between the grinding wheel and the camshaft. Another object of the invention is to provide an automatic cam grinding machine in which the rock bar for supporting a camshaft to be ground is rocked transversely relative to the grinding wheel to produce the desired and predetermined contour on the work blank, and in which the path of oscillation of the rock bar is shifted to produce a relative transverse or grinding feed between the cam blank and the grinding wheel. A further object of the invention is to provide an electrically controlled hydraulic mechanism for controlling the main control valve which in turn controls the admission of fluid to the table positioning and the rock bar cylinder. A further object of the invention is to provide a combined wheel feeding and pilot valve which serves to shift the main control valve to control the cycle of operation. Another object of the invention is to provide an electrically operated mechanism to actuate the pilot valve after a predetermined cycle of operation to move the various parts of the machine into position for grinding the next cam. Another object of the invention is to provide a mechanism for rendering the cycle control mechanism inoperative during the longitudinal traversing movement of the table. Another object of the invention is to provide an automatic cam grinding machine with a cycle control mechanism which is rendered inoperative by movement of the main control lever. Other objects will be in part obvious or in part pointed out hereinafter.

The invention accordingly consists in the features of construction, combinations of elements, and arrangements of parts, as will be exemplified in the structure to be hereinafter described, and

the scope of the application of which will be indicated in the following claims.

In the accompanying drawings, in which is shown one of various possible embodiments of the mechanical features of this invention:

Fig. 1 is a front elevation of the improved automatic cam grinding machine;

Fig. 2 is a cross sectional view, on an enlarged scale, taken approximately on the line 2—2 of Fig. 1, showing parts of the grinding wheel positioning mechanism in elevation;

Fig. 3 is a combined hydraulic piping diagram and electrical wiring diagram;

Fig. 4 is a fragmentary front elevation of the control apron, on an enlarged scale;

Fig. 5 is a fragmentary cross sectional view through the control mechanism, on an enlarged scale, taken approximately on the line 5—5 of Fig. 1;

Fig. 6 is a horizontal sectional view, on a slightly reduced scale, through the valve mechanism, taken approximately on the line 6—6 of Fig. 5;

Fig. 7 is a fragmentary cross sectional view, through the rock bar motor, taken approximately on the line 7—7 of Fig. 1;

Fig. 8 is a fragmentary perspective view of the rock bar, work drive mechanism, and work feed motor;

Fig. 9 is a longitudinal sectional view of the feed control or cycle pilot valve;

Fig. 10 is a longitudinal sectional view of the main control valve;

Fig. 11 is a cross sectional view, on an enlarged scale, through the rock bar and the master cam roller indexing mechanism;

Fig. 12 is an end elevation, on an enlarged scale, of the cycle timing mechanism with the cover removed, taken approximately on the line 12—12 of Fig. 1;

Fig. 13 is a cross sectional view, through the cycle timing mechanism, taken approximately on the line 13—13 of Fig. 12;

Fig. 14 is a fragmentary plan view of the rock bar motor shown in Fig. 7;

Fig. 15 is a fragmentary end elevation of the master cam roller, the fluid actuating motor therefor, and associated parts;

Fig. 16 is a longitudinal sectional view through the master cam roller and fluid motor, taken approximately on the line 16—16 of Fig. 15;

Fig. 17 is a cross sectional view through the master cam roller fluid motor, taken approximately on the line 17—17 of Fig. 16; and

Fig. 18 is a cross sectional view through the

work feed adjusting mechanism, taken approximately on the line 18—18 of Fig. 16.

A cam grinding machine has been illustrated in the drawings having a base 20 which supports a longitudinally movable work table 21 on the usual flat way 22 and V-way 23. The base 20 also supports a transversely movable wheel slide 25 on the V-way and flat way (not shown) for a transverse adjustment toward and from the work supporting table 21. The wheel slide 25 rotatably supports a grinding wheel spindle 26 which is journalled in bearings (not shown). The wheel spindle 26 carries a grinding wheel 27 which is arranged to present a peripheral cylindrical grinding face to the work piece for a grinding operation. The grinding wheel 27 and its supporting spindle 26 may be driven in any suitable manner, such as by means of an electric motor 28 mounted on top of the wheel slide 25. A multi-grooved pulley 29 is mounted on the outer end of a motor armature shaft 30 and is connected by multiple V-belts with a multi-grooved pulley 32 mounted on the outer end of the wheel spindle 26.

The grinding wheel slide 25 is arranged for a transverse movement relative to the base 10 for the purpose of initially setting up the machine for a given grinding operation and also for the purpose of feeding the wheel transversely prior to automatic dressing or truing of the wheel after a grinding operation has been completed. A feeding mechanism of the nut and screw type has been illustrated comprising a feed screw 35 which is rotatably supported in bearings 36 and 37 which are in turn fixedly mounted in portions of the base 20. A half nut 38 is fixedly mounted on the under side of the wheel slide 25 and meshes with or engages the feed screw 35 so that when the feed screw 35 is rotated, a transverse movement is imparted to the wheel slide 25 to the half nut 38.

To facilitate manual adjustment of the grinding wheel 27 and wheel slide 25, a manually operable hand wheel 40 is mounted on the outer end of a hub 41 which is rotatably supported on a stud 42. The stud 42 is fixedly supported on a bracket 43 fixedly secured to the base 20. The inner end of the sleeve 41 is provided with a pinion 44 which meshes with a gear 45. The gear 45 is rotatably supported on a stud 46 which is fixedly supported on the bracket 43. The gear 45 meshes with a gear 47 mounted on the outer end of a rotatable shaft 48 which is journalled in bearings 49, 50 and 51 in the base 20. The inner end of the shaft 48 supports a gear 52 which meshes with a gear 53 mounted on the outer end of the feed screw shaft 35. It will be readily apparent from the foregoing disclosure that the grinding wheel 27 and the wheel slide 25 may be adjusted transversely by the manual rotation of the hand feed wheel 40 to adjust the position of the wheel in setting up the machine for a predetermined grinding operation.

To facilitate automatic adjustment of the wheel so as to advance the wheel automatically for a truing operation, a ratchet wheel 55 is fixedly mounted on the periphery of the sleeve 41. A feed pawl 56 is mounted on a stud 57 which is in turn carried by an oscillatable pawl carrier 58 which is rotatably supported on a hub portion of the ratchet wheel 55. The pawl carrier 58 is oscillated automatically by a table dog prior to the grinding wheel truing operation in a manner substantially the same as that disclosed in the prior United States patent to Belden

and Silven No. 2,022,178 to which reference may be had for details of disclosure not contained herein.

The longitudinally movable work table 21 supports a pivotally mounted rock bar 60 which is supported in bearings 61 (only one of which has been illustrated in the drawings) on the table 11 (Figs. 2 and 8) and is arranged so that it may be rocked about an axis which is substantially parallel to the axis of the grinding wheel 27. The rock bar 60 is provided with a rotatable headstock spindle 62 having a headstock center (not shown). The rock bar also supports a footstock 63 having a footstock center 64. The headstock center and the footstock center 64 are arranged rotatably to support a camshaft 65 to be ground.

Master cams and roller

In order that the cams on the camshaft 65 may be ground to a predetermined size and contour, it is desirable to provide a series of master cams 66 on a master cam spindle 67 which is rotatably supported on the rock bar 60 for controlling the rocking movement of the rock bar 60 so as to rock the camshaft 65 being ground transversely toward and from the periphery of the grinding wheel 27 so as to generate a predetermined shape or contour thereon. A plurality of master cams 66 are mounted on the master cam spindle 67 which is either formed integral with or fixedly secured to the headstock spindle 62 and the headstock center (not shown). The master cams 66, the master cam spindle 67, and the headstock spindle 62 are preferably arranged as illustrated in Fig. 8 in axial alignment with the camshaft 65 to be ground. A master cam follower roller 68 is slidably and rotatably supported on a rotatable shaft 69 which is journalled in suitable bearings supported in fixed relation with the work table 21. The master cam roller 68 is preferably indexed automatically as the table 21 is indexed longitudinally to position the master cam roller 68 opposite the master cam 66 which corresponds to the cam being ground on the camshaft 65. The master cam roller indexing mechanism is illustrated in Fig. 11 which will be hereinafter described. For a detailed disclosure of the automatic shifting of the master cam roller, reference may be had to the prior United States Patent No. 1,783,755 to Trefethen and Belden dated December 2, 1930, and also to the United States Patent No. 2,022,178 to Belden and Silven dated November 26, 1935.

Rock bar actuating mechanism

In order that the master cams 66 may be maintained in operative engagement with the master cam roller 68 during the grinding operation on a cam, a yieldable pressure device is provided which serves yieldably to maintain the master cam 66 in operative contact with the follower roller 68. As shown in the drawings, a headstock frame 70 is detachably secured to a dovetailed slideway 71 formed on the upper surface of the rock bar 60. The headstock frame 70 carries a stud 72 which is pivotally connected to a block 73 fixedly mounted on the right-hand end of a rod 74 by means of a tapered pin 75. The rod 74 is slidably keyed to a hollow tubular member 76 by a key 77. A spring 78 surrounds the rod 74 and is interposed between an integral flange 79 formed on the rod 74 and a slidable sleeve 80 which is slidably mounted on the rod 74. A spring 81 surrounds the other end of the rod 74 and is interposed between the sleeve 80 and an adjustable collar 82 which is screw threaded into a threaded portion 75

83 within the hollow tubular member 76. The compression springs 78 and 81 serve to exert a pressure on the rod 74 toward the right (Fig. 7) tending to rock the rock bar in a clockwise direction (Fig. 7) so as to maintain the master cam roller 66 in operative engagement with the master cam roller 68 during a grinding operation. A single spring might be employed instead of the two spaced springs 78 and 81, if desired, and interposed between the flange 79 and the adjustable stop plate 82, in which case the slidable sleeve 80 may be dispensed with.

By adjusting the position of the stop plate or collar 82 within the screw threaded portion 83, the springs 78 and 81 may be compressed so as to exert the desired predetermined pressure between the master cam 66 and the master cam roller 68.

To facilitate adjustment of the compression of the plate 82 readily to adjust the compression of the springs 78 and 81, the plate 82 is provided with a central aperture 84 which is preferably square or rectangular in shape. A rod 86 has a squared-off end which slidably engages the aperture 84 in the plate 82. The rod 86 is carried by a hollow cup-shaped member 88 which is rotatably supported by a plate 89 which forms a circular slideway to engage a flange 90 projecting from the edge of the cup-shaped member 88 so that the cup-shaped member 88 may be readily rotated to turn the adjustable plate 82 so as to vary the compression of the springs 78 and 81 as desired. A binding screw 91 is provided which engages a portion of the flange 90 to facilitate locking the cup 88 in adjusted position after the compression of the springs 78 and 81 has been adjusted to the desired extent.

Hydraulic actuation—Rock bar

40 A fluid pressure mechanism is provided to rock the bar 60 to an inoperative position automatically before the table 21 is traversed or indexed, so that the master cam 66 and follower 68 and product camshaft 65 and grinding wheel 27, respectively, are separated before the table 21 starts its traversing or indexing movement. This mechanism may comprise a fluid pressure cylinder 90 having a piston 91 slidably mounted therein. The piston 91 is preferably formed as illustrated 45 as an integral projecting flange of the tubular member 76 which is slidably keyed to the rod 74 which in turn is pivotally connected to a stud 72 to move the rock bar. When fluid under pressure is admitted through a pipe 92 into a cylinder chamber 93 within the cylinder 90, the piston 91 moves toward the left (Fig. 7), carrying with it the tubular member 76, the adjustable thrust plate 82 and, through the springs 81 and 79, serves to cause an endwise movement of the rod 74 which operates through the pivotally supported block 72 to rock the rock bar 60 in a counter-clockwise direction (Fig. 7) so as to separate the master cam 66 from the master cam roller 68. During this movement of the rock bar, fluid 50 within the cylinder chamber 94 is exhausted through a pipe 95. The valve mechanism for controlling the admission of fluid to the cylinder 90 will be described hereinafter.

An adjustable stop collar 96 is screw threaded 55 onto the periphery of the block 73 and is arranged to engage the end surface 97 of the cylinder 90 to serve as a stop to limit the movement of the piston 91 toward the left (Fig. 7) and also to limit the rocking and separating movement of the rock bar 60. A lock collar 98 serves to facilitate lock-

ing the stop collar 96 in the desired adjusted position. In order to permit a free movement of the cylinder 90 during the rocking movement of the bar 60, the cylinder 90 is provided with diametrically opposed trunnions 99 and 100 which are supported in bearings 101 and 102, respectively, within the headstock frame which is fixedly supported relative to the table 21. The entire headstock end of the table is provided with a casing 103 which encloses the entire mechanism 101 to prevent grit and other foreign matter from getting within the operating parts. In order to facilitate adjustment of the rock bar springs 78 and 81, a cover plate 104 is hinged to the front of the casing 103 and is arranged so that the cup-shaped member 88 may be rotated to adjust the springs as desired.

The work supporting table 21 is moved longitudinally relative to the base 20 by means of a fluid pressure operated mechanism comprising a cylinder 110 which is fixed to the under side of the table 21. A pair of pistons 111 and 112 are slidably supported within the cylinder 110.

The pistons 111 and 112 are each mounted on the inner ends of a pair of piston rods 113 and 114, respectively, which are in turn fixedly connected at their outer ends by hollow brackets 115 and 116, respectively. The brackets 115 and 116 serve to anchor the outer ends of the piston rods relative to the base 20. In order to permit expansion of the parts, the length of the piston rods 113 and 114 is such that the pistons 111 and 112 are spaced from each other by an amount sufficient to take care of expansion of the parts during the normal operation of the machine. 30 The admission of fluid under pressure to either a cylinder chamber 117 or 118 through a pipe 119 or 120, respectively, is controlled by a table controlling or reversing valve 121.

Table control valve

40 The table control valve 121 is preferably a piston type valve comprising a valve stem 122 having formed integral therewith valve pistons 123, 124, 125 and 126. Fluid under pressure from a source 45 to be hereinafter described passes through a pipe 127, into a valve chamber 128 located between the valve pistons 124 and 125, and in the position of the valve illustrated in Fig. 3, passes through the pipe 120 into the table cylinder chamber 118 to cause the table 21 and cylinder 110 to move toward the right. During this traversing or indexing movement of the table 21, fluid is exhausted from the cylinder chamber 117, through the hollow piston rod 113, the bracket 115, pipe 119, into a valve chamber 129 in the table control valve 121, and out through an exhaust pipe 130. The connection of the table control valve with the other operating parts of the fluid pressure system will be hereinafter described.

Work rotation

As above described, the headstock spindle 62, the master cam spindle 67, and the camshaft 65 are arranged in axial alignment with each other and the camshaft 65 to be ground is provided with a driving dog 133 which serves to connect the camshaft 65 so as to rotate with the headstock spindle 62 and the master camshaft 67. 65 The master cam spindle 67 and the headstock spindle 62 are driven by a motor driven driving mechanism contained within the headstock casing 103 (Fig. 3). This mechanism comprises an electric motor 134 (Fig. 8) having a motor shaft 135 which carries a worm 136. The worm 136 70

- meshes with a worm gear 137 mounted on one end of a shaft 138 which is preferably arranged parallel to the axis of oscillation of the rock bar 60. The shaft 138 carries at its other end a multi-grooved pulley 139 which is connected by multiple V-belts 140 with a multiple grooved pulley 141 mounted on the end of a driven shaft 142 which is arranged in axial alignment with the axis of oscillation of the rock bar 60. A sprocket 143 is mounted on the other end of the shaft 142 and is connected by a link chain 144 with a sprocket 145 mounted on the left-hand end of the master cam spindle 67. The shafts above described are mounted in suitable bearings (not shown) within the headstock casing 103 on the table 21.
- It will be readily apparent from the foregoing disclosure that when the electric motor 134 is set in rotation, a rotary motion will be transmitted through the shaft 135, the worm 136, the worm gear 137, the shaft 138, the pulley 139, the shaft 142, the V-belts 140, the pulley 141, the shaft 142, the sprocket 143, the link chain 144, and the sprocket 145 to rotate the master cam spindle 68 which in turn transmits a rotary motion to the master cams 66 and the camshaft 65 to be ground. Due to the fact that the master cam 66 is maintained in yielding engagement with the master cam roller 68 by means of the springs 78 and 81 above described, when the master cams 66 are rotated, a rocking motion will be transmitted to the rock bar 60, which serves to oscillate the camshaft 65 toward and from the peripheral grinding surface of the grinding wheel 27 to grind and generate a predetermined contour on the cam being ground.

Master cam roller indexing mechanism

The master cam roller 68 is preferably indexed longitudinally automatically in timed relation with the indexing movement of the table 21 so that the master cam roller 68 is arranged in alignment with the master cam corresponding to the product cam on the camshaft 65 to be ground. This is preferably accomplished in a manner similar to that disclosed in the prior United States Patent No. 1,783,755 to Belden and Trefethen and also in the United States Patent No. 2,022,178 to Belden and Silven dated November 26, 1935, to which reference may be had for details of disclosure not found herein. The base 20 is provided with a dog bar 150 (Fig. 11) having a plurality of adjustably positioned dogs 151 which are arranged in spaced relation with each other and spaced in accordance with the spacing of the cams on the camshaft 65 to be ground. A star wheel 152 is mounted at the lower end of a vertically positioned rotatable shaft 153 which is journaled in a housing 154 carried by the headstock bracket 60 155 which is rigidly secured to the table 21. The upper end of the shaft 153 carries a gear 156 which meshes with a gear (not shown) mounted on the lower end of a rotatable shaft 157. A gear 158 is mounted on the upper end of the shaft 65 157 and meshes with a rack bar 159 which is fixedly mounted on a non-rotatable slidably mounted shaft 160. The shaft 160 carries a yoked member 161 (Figs. 11 and 16) which is arranged to engage a flange 162 which is formed integral with a slidably mounted sleeve 163 which is slidably supported on the shaft 69. The sleeve 163 supports an anti-friction bearing 164 which in turn rotatably supports the master cam follower roller. It will be readily apparent from the foregoing disclosure that when the table 21 is tray-

ersed or indexed longitudinally to position successive cams on the camshaft 65 to be ground in operative relation with the grinding wheel 27, a corresponding indexing movement will be imparted to the master cam follower roller 68 automatically to position it in operative relation with the master cams 66 opposite to the master cam 66 which corresponds with the product cam on the shaft 65 to be ground.

Grinding feed

In order to attain one object of this invention, it is desirable to impart a relative approaching and receding movement between the camshaft to be ground and the grinding wheel. In the preferred form, a feeding movement is imparted to the camshaft being ground so that in addition to moving toward and from the periphery of the wheel to grind the desired contour on a cam blank, the camshaft axis is also advanced toward the grinding wheel axis to grind the cams to a predetermined size. The camshaft support or rock bar, being a lighter element, may be more readily and accurately fed and controlled, especially in a comparatively fast cycle of operation, than a heavy massive grinding wheel slide. A feeding mechanism is, therefore, provided whereby the arc of oscillation of the rock bar is shifted as the grinding proceeds to produce the desired grinding feed and thereby sizing of the cam being ground. This feeding movement is preferably accomplished by bodily moving the master cam follower roller 68 to cause the work axis gradually to approach the wheel axis and thereby to grind the cam blank on the shaft 65 to the required size. As illustrated in the drawings, the master cam roller shaft 69 is provided at its opposite ends with eccentric trunnion portions 170 (Fig. 16) only one of which has been illustrated in the drawings. The trunnion portions 170 are mounted in suitable bearings 171 which are fixedly mounted on the frame of the headstock within the casing 103. In order to obtain the desired feeding movement, the trunnions 170 are rocked about their axis which rocks the eccentric shaft 69 and thereby produces an eccentric feeding movement to the master cam follower roller 68.

A hydraulic actuating mechanism is provided for controlling the oscillation of the trunnions 170 to rock the eccentric shaft 69 which comprises a single-vane type fluid motor 172 having a fluid chamber 173. A single vane 174 is fixedly mounted on a motor shaft 175. Fluid under pressure is admitted through a passage 176 and a port 177 into the motor chamber 178 to cause the vane to rotate in a counterclockwise direction (Figs. 3 and 17) to produce the desired infeeding movement of the camshaft 65 to grind successive cams to a predetermined size. A feed control mechanism is provided for the motor 172 so that the relative infeeding movement between the cam and the grinding wheel 27 may be readily controlled. When fluid under pressure is admitted through passage 176 and a port 177 into the motor chamber 178 to move the vane 174 in a counterclockwise direction (Figs. 3 and 17), the fluid within the chamber formed at the other side of the vane 174 serves to close a ball check valve 179 and thereafter to cause fluid within said chamber to exhaust through a passage 180 and an adjustable needle valve 181 and through a passage 182. Similarly, when the fluid under pressure to the feed motor 172 is reversed, fluid enters through the passage 182, 75

opens the ball check valve 179 and moves the vane 174 rapidly in a clockwise direction (Figs. 3 and 17) to cause the camshaft 65 being ground to recede from the grinding wheel.

5 The fluid motor 172 is operatively connected to oscillate or rock the shaft 170 to produce the desired feeding movement. It is desirable to provide a suitable adjusting mechanism between the fluid motor 172 and the shaft 170 so that the 10 extent of rocking movement of the shaft 170 and the eccentric master cam roller supporting shaft 69 may be precisely adjusted so as to regulate the extent of the infeeding movement. A cam 185 is fixedly mounted on the end of the motor shaft 175. The cam 185 is engaged by a follower 186 carried by an oscillatable member 187 which is pivotally supported on a stud 188. The roller 186 is maintained in operative contact with the cam 185 by means of a spring 189. A rock 20 arm 190 is fixedly mounted on the end of the shaft 170 and is normally urged in a counterclockwise direction by means of a spring 191 so that its under plane surface 192 engages an adjustable roller 193 carried by the oscillatable 25 member 187. The roller 193 is carried by a stud 194 which is supported on a slide block 195. The slide block 195 may be adjusted longitudinally along a slideway 196 by means of a rotatable screw 197 which is supported by and is held 30 against endwise movement in a bearing 198 and is screw threaded through an aperture in the slide 195. By varying the position of the roller 193 along its slide surface 196, the extent of feeding movement transmitted by the motor 172 may 35 be varied, as desired. For each infeeding operation, the vane 174 of motor 172 revolves one half turn with the shaft 175.

It will be readily apparent from the foregoing construction that by adjusting the position of the 40 slide 195 along its slideway 196, the lever arm between the point of contact of the roller 193, the surface 192 and the axis of the pivot stud 188 will be varied, thus varying the amount of motion transmitted by the oscillatable member 45 45 to rock the shaft 170 so as to produce the desired infeeding movement between the cam-shaft and grinding wheel 27. It should be noted that the surface 192 is a plane surface which is positioned when roller 186 is in engagement with the concentric portion of the cam 185 so that it coincides with the axis of the stud 188. If the roller 193 is adjusted longitudinally so that its line of contact with the surface 192 coincides with the axis of the stud 188, no rocking motion 50 will be transmitted to the lever 190 and consequently no feed will be imparted to the master cam roller. If the roller 193 is adjusted toward the right away from the axis of the stud 188, then the rocking motion of the shaft 170 and of 55 the roller 68 will be increased. By manipulation of the screw 197 to position the roller 193, a predetermined amount of feeding movement may be obtained to grind the cam blanks on the cam-shaft 65 to the desired size. By manipulation 60 of the needle valve 181, the rate of infeed may be adjusted as desired. It should be noted that the vane 174 of the motor 172 makes one-half a revolution for each infeeding movement. To 65 facilitate adjustment of the roller 193, an index point is provided on the slide 195 and a graduated scale is provided adjacent to the edge of the slideway 196 so that the roller 193 may be readily set at the required distance from the stud 188 to produce the desired infeeding movement.

70 The slide 195 is preferably slotted, as indicated

in Figs. 15 and 18, and a push and pull screw is provided between the spaced portions thereof adjacent to the slot to facilitate locking the slide 195 in adjusted position relative to the screw 197.

Cycle pilot feed control valve

The admission and exhaust of fluid to and from the feed motor 172 is controlled by a feed control or cycle pilot valve 200. This valve is 10 preferably of a piston type comprising a valve stem 201 having formed integral therewith a plurality of valve pistons 202, 203, 204, and 205.

A fluid pressure system is provided for conveying fluid under pressure to the various mechanisms of the machine and comprises a reservoir or sump 206. A motor driven fluid pressure pump 207 pumps fluid through a pipe 208 from the reservoir 206 and forces it through a pipe 209, a pipe 210, into a valve chamber 211 located 20 between the valve pistons 203 and 204 of the valve 200. In the position of the valve illustrated in Fig. 3, fluid under pressure passes from the valve chamber 211, through a pipe 212, the passage 176 and the port 177, to cause the vane 174 25 of the feed motor 172 to move in a counterclockwise direction (Figs. 3 and 17) to cause an infeeding movement of the camshaft 65. During this movement, fluid under pressure exhausts from the chamber on the opposite side of the 30 vane 174, out through the adjustable needle valve 181 which regulates the speed of movement thereof, and out through the passage 182 and a pipe 213, into a valve chamber 214 located between the valve pistons 204 and 205 of the feed control- 35 cycle pilot valve 200 which exhausts through pipe 215 into the reservoir 206.

Similarly, when the valve stem 201 is moved toward the right (Fig. 3), the passage of fluid under pressure to and from the motor 172 is reversed so as to pass fluid under pressure through the pipe 213 and passage 182 to cause the vane 174 of the motor 172 to move in a clockwise direction (Figs. 3 and 17) to separate the cam being ground from the grinding wheel 27. A spring 216 45 serves normally to hold the valve stem 201 in its extreme right-hand position (Fig. 3), and a solenoid 217 which is connected to the left-hand end (Fig. 3) of the valve stem 201 serves when energized to shift the valve stem 201 to its extreme 50 left-hand position so as to produce an infeeding movement. The electrical control for the solenoid 217 will be hereinafter described.

The feed control or cycle pilot valve 200 also serves to control the admission to and exhaust 55 of fluid from the rock bar cylinder 90. The pipe 212 (Fig. 3) is connected with the pipe 95 to pass fluid under pressure to the cylinder chamber 94 so as to rock the bar 60 and maintain the master cam 66 in operative engagement with the master 60 cam roller 68 when fluid is admitted through the pipe 212 to start an infeeding movement of the work toward the grinding wheel face.

Main control valve

65

The feed control or cycle pilot valve 200 serves also as a pilot valve for actuating a main control valve 220. The main control valve 220 is a piston type valve comprising a valve stem 221 having formed integrally therewith a plurality of valve 70 pistons 222, 223 and 224. When the cycle pilot or feed control valve 200 is in the position illustrated in Fig. 3, fluid under pressure passing from the valve chamber 211 passes through a pipe 225, into a valve chamber 226 at the left-hand end of 75

the main control valve 220 (Fig. 3) and serves to move the valve stem 221 into its extreme right-hand position, as indicated. During the shifting movement of the valve into the right-hand position, fluid exhausts from a chamber 227 at the right-hand end of the main control valve 220, through a pipe 228 which connects to exhaust fluid into the pipe 213, through the valve chamber 214 and pipe 215, to the reservoir.

Similarly, when the feed control cycle pilot valve shifts to its reverse position, fluid under pressure passes through the pipe 228 into the cylinder chamber 227 to shift the main control valve 220 to its extreme left-hand position. The functions of the main control valve will be herein-after described.

Pilot valve

A pilot valve 230 is provided for the purpose of automatically shifting the reverse or table control valve 121. The pilot valve 230 is a piston type valve comprising the valve stem 231 having formed integrally therewith a plurality of valve pistons 232, 233, 234 and 235. The valve stem 231 is normally held in a central position by means of a spring 236. The outer end of the valve stem 236 is provided with a spool-shaped member 238 which is arranged to be actuated by a stud 239 carried by a lever 240. The lever 240 is supported on a rock shaft 241 which supports at its other end a pilot valve actuating lever 242 which is actuated by dogs on the table, as will hereinafter be described.

Fluid under pressure from the valve chamber 129 in the table control valve 121 passes through a pipe 243 into a valve chamber 244 located between the valve pistons 233 and 234. In the position of the valve as illustrated in Fig. 3, the pressure balances against the pistons 233 and 234. When a table dog engages the lever 242 to rock it in a clockwise direction so as to shift the valve stem 231 toward the left (Fig. 3), fluid under pressure within the chamber 244 passes out through a pipe 245, into a valve chamber 246 formed in the left-hand end of the table control valve 121, and serves to shift the valve 121 toward the right into its reverse position. During this movement, fluid within the valve chamber 247 in the opposite end of the reverse or table control valve 121, passes through a pipe 248 into a valve chamber 249 located between the valve pistons 234 and 235 and exhausts through a pipe 250 into the reservoir. Similarly, when the lever 242 is rocked in a counterclockwise direction (Fig. 3), the valve stem 231 is moved toward the right and fluid under pressure from the valve chamber 244 passes through the pipe 248 in the valve chamber 247 to shift the table control valve 121 toward the left in a reverse position.

Table indexing movement

The table 21 is traversed or indexed longitudinally and automatically by means of a fluid pressure mechanism, above described, which comprises a cylinder 110 containing pistons 111 and 112 which are connected by means of the hollow piston rods 113 and 114, respectively, with hollow brackets 115 and 116, respectively, on the base 20. The admission of fluid to either cylinder chamber 117 or 118 is controlled by the table controlling a reversing valve 121. Fluid under pressure from the pump 207 passes through the pipe 209, a pipe 252, into a valve chamber 253 located between the valve piston 222 and 223 in the main control valve 220, and through a pipe 254, into the valve

chamber 128 in the table control or reversing valve 121, and from there through a pipe 243, into the valve chamber 244 of the pilot valve 230. In the position of the main control valve illustrated in Fig. 3, the pipe 254 is cut off by the piston 222 and consequently no fluid can flow to the table control valves or to the table cylinder during the infeeding movement of the work support.

Wheel truing mechanism

In a machine of this type, the grinding wheel is preferably trued automatically in between operations, that is after one camshaft has been ground and before the new shaft is ground upon, so that a trued grinding wheel face will be presented at the start of each grinding operation.

A truing apparatus comprising a bracket 255 is fixedly mounted on the table 21 and carries a truing tool which may be adjusted relative to the bracket 255 by means of a micrometer adjusting screw 259. The details of the truing mechanism have not been illustrated, since this feature is not considered to be part of the present invention. For further details of this mechanism, reference may be had to the prior United States patent to Belden and Silven No. 2,022,178 dated November 26, 1935. The truing mechanism in the present case is substantially as shown in the prior patent except that it is arranged directly below the footstock center 64 instead of above the center. The diamond or truing tool, however, is held in a rigid fixed position and is arranged to true the grinding wheel when it is in its rearmost position. In the present invention, the grinding wheel 27 is not moved toward the work piece for a feeding movement but is held in a relatively fixed position and is adjusted only to compensate for wheel wear and truing. After the last cam on the camshaft has been ground, the feed motor 172 causes the work to recede from the grinding wheel 27. The table 21 is then given an additional traversing movement to carry the previously adjusted diamond truing tool across the operative face of the grinding wheel to true the same.

Slow traverse—Truing

The normal traversing or indexing movement of the table is comparatively rapid to reduce the loss of time between successive grinding operations. The normal speed is not at all suited for a truing operation which requires a very slow, uniform relative traversing movement between the truing tool and the grinding wheel. To obtain a slow truing traversing movement of the table, a slow speed valve 260 is provided through which fluid exhausting from the table cylinder 110 passes. When fluid is exhausted from the cylinder 110 through either the pipe 119 or 120, it passes through either the valve chamber 129 or a valve chamber 287, respectively, and from there through a slow speed control valve 260, into the reservoir 206. The slow speed valve 260 is a piston-type valve comprising a valve stem 261 having formed integrally therewith valve pistons 262, 263, 264, 265 and 266. The outer end of the valve stem 261 is provided with a spool-shaped member 267 which is engaged by a stud 268 carried by the lower end of a rock arm 269 which is in turn supported on a rock shaft 270. The rock shaft 270 is journaled in a suitable bearing 271 which is fixedly mounted relative to the base 20. The rock shaft 270 projects from the front of the machine base and

carries on its outer end a rock arm 272 having a roller 273 mounted at its upper end. The roller 273 is rotatably supported on a stud 274. The roller 273 is arranged in the path of a cam surface 275 on a truing dog 276 which will be hereinafter described. When the table 21 is traversed toward the left (Figs. 1, 3 and 4) after grinding the last cam on the camshaft to be ground, the cam surface 275 of the truing dog 276 engages the roller 273 and rocks the arm 272, the rock shaft 270, and the arm 269 in a counterclockwise direction (Fig. 4) which serves to move the valve stem 261 of the slow speed valve 260 toward the right (Fig. 3). Similarly, when the table traverses in the opposite direction and when the cam 275 moves toward the right and leaves the roller 273, the arm 272, the rock shaft 270 and lever 269 are rocked in a clockwise direction (Figs. 3 and 4). A spring 277 within the valve 260 aids in shifting the valve 260 toward the left (Fig. 3) and thereby allows the table 21 again to be traversed at its normal indexing or traversing speed. Fluid exhausting from the table cylinder 110 through the pipe 119 and valve chamber 129 normally passes out through the pipe 130 into a valve chamber 280 and passes out through a pipe 281 and a pipe 282 to the reservoir 206. In the position of the valve as shown in Fig. 3, the ports are wide open so that fluid may flow unrestricted from the pipe 130, through the pipes 281 and 282, into the reservoir 206. When the table moves into a truing position, the valve stem 261 is moved toward the right (Fig. 3) against the compression of the spring 277 so that the valve piston 265 closes the port at the end of the pipe 130, after which fluid from the pipe 130 exhausts through an adjustable needle valve 283 and a pipe 284 which connects with the pipe 282 to return the fluid to the reservoir 206. By manipulation of the valve 283, the desired truing speed of the table 21, in its traverse towards the right, may be obtained.

Similarly, when the table control valve 121 shifts to reverse the direction of travel of the table and start it moving toward the left, during the truing operation, fluid within the chamber 118 of the table cylinder 110 will exhaust through pipe 120 into the valve chamber 287 located between the valve pistons 123 and 124 and passes out through a pipe 288 and a pipe 289, into a valve chamber 290 in the slow speed valve 260 located between the valve pistons 262 and 263 and through a pipe 291 which connects with the pipe 282 to return the fluid to the reservoir 206. In the position of the slow speed valve 260 (Fig. 3), unrestricted passage of fluid is permitted through the valve chamber 290. When the valve 260 is in a truing position, however, the port at the end of the pipe 289 is closed by the valve piston 262, after which fluid exhausting through the pipe 288 passes through an adjustable needle valve 292 into the pipe 282 and returns to the reservoir 206. By manipulation of the needle valve 292, the truing speed of the table and truing tool in the reverse direction (toward the left) may be varied as desired. By manipulation of the adjustable needle valves 283 and 292, the truing speed of the table may be adjusted in its movement in either direction so that the table travels either at the same or different speeds when moved in opposite directions.

In order to obtain the maximum production, the table 21 must be traversed at a rapid rate of speed during its idle return stroke and also

at a fast indexing speed during the grinding stroke of the table. An adjustable stop screw 261a serves to adjust the left-hand end position of the valve 260. By manipulation of the screw 261a, the aperture of the port at the end of pipe 130 may be varied to regulate the table indexing speed. The port at the end of the pipe 289 is arranged so that this port is wide open during the idle stroke of the table so that the table returns at a maximum speed. On the long return stroke, the table can be traveled at a more rapid rate than during the short indexing movements. By adjusting the screw 261a to vary the aperture of the port at the end of the pipe 130, the indexing speed may be increased or decreased to obtain the desired results.

Truing dog

It is desirable that the speed of movement of the table 21 be slowed down gradually to a truing speed to prevent shocks and vibrations which would occur with a sudden change of speed. To accomplish this result, the truing dog 276 is provided with a pivotally mounted latch block 293 which is pivotally supported on a stud 294 which is fixed to the truing dog 276. The swinging movement of the block 293 in a counterclockwise direction is limited by an adjustably positioned stop 295. When the table 21 is moving toward the left into a truing position, the roller 273 engages a surface 296 before the roller contacts with the cam 275 to rock the lever 272 and thereby shift the slow speed valve to slow down the table movement a short distance before the diamond or truing tool engages the wheel so as to prevent any shock or vibration of the table as the truing operation starts. The truing operation continues until an adjustable dog 297 engages the lever 242 to rock it in a counterclockwise direction to reverse the table movement and to start the traverse of the table in the opposite direction. As the truing tool starts traversing across the wheel in a direction toward the left, the roller 273 engages the end of the pivotally mounted latch block 293 and rocks it in a clockwise direction so as to allow the roller 273 to follow the cam surface 275 quickly to return the table 21 to a normal traversing or indexing speed.

It may be desirable at times during the operation of the machine to render the truing mechanism inoperative so that several camshafts might be ground without automatically truing the wheel between shafts. To accomplish this result, a dog 298 is pivotally supported by a stud 299 on the truing dog 276. The position of the dog 298 is governed by a stop screw 406 which serves adjustably to position the dog 298 relative to the truing dog 276 so that it may be positioned in the path of or out of the path of the lever 242. A spring 407 serves to hold the pivotally mounted dog 298 in position against the stop screw 406. In the position of the parts as shown in Fig. 4, the dog 298 is shown out of the path of the lever 242 so that after the last cam on the shaft has been ground, the table will be moved beyond the last cam on the shaft and the wheel will be automatically trued. In case it is desired to stop the machine without truing the grinding wheel after a camshaft has been ground, the stop screw 406 is adjusted to lower the dog 298 so that the dog will engage the lever 242 when the table moves toward the left and reverse the table movement without permitting the truing tool to engage and true the wheel.

Also, if it is desired, in setting up the machine with a new grinding wheel, to true a considerable amount of material off the wheel, the table may be moved into a truing position so that the upper end of the lever 242 is positioned between the dogs 297 and 298 at which time the dog 298 may be depressed so that the table will be continuously reciprocated as governed by the dogs 297 and 298 until the desired amount has been trued off the periphery of the wheel, after which the stop screw 406 may be adjusted to raise the dog 298 and allow the table to traverse toward the right until the dog lever 340 engage a table stop dog 405.

15 *Cycle control mechanism*

In order to attain one of the objects of this invention and to obtain the maximum efficiency from the machine, a cycle control device is provided which serves, after a cam has been rotated through a predetermined number of rotations in operative grinding engagement with the grinding wheel 27, to actuate the cycle pilot or feed control valve 290 which in turn serves to actuate the main control valve and thereby to admit fluid under pressure to the rock bar cylinder 99 to rock the master cam 66 out of engagement with the follower 68 and thereby separate the cam blank being ground from the grinding wheel 27 to admit fluid to the feed motor 172 to shift the position of the master cam roller 68, and then to admit fluid under pressure to the table traversing cylinder 110 automatically to index the table 21 to present the next cam blank on the camshaft 65 to be ground into operative relation with the grinding wheel 27. This is preferably accomplished by means of a cycle control or counting device 300 which is contained within a casing located on the right-hand end of the headstock casing 103 (Fig. 1).

The counting device 300 comprises a ratchet wheel 301 which is keyed to a rotatable shaft 302. A pawl 303 is carried by a stud 304 on a bracket 305 which is adjustably mounted on the upper end of an arm 306. The arm 306 is adjustably mounted on a bracket 307 which is rigidly clamped on the dovetailed portion 71 of the rock bar 60. A spring 308 serves normally to hold the pawl 303 in an operative position against a stop 308a on the bracket 305. It will be readily apparent from the foregoing disclosure that each time the rock bar 60 is oscillated, the pawl 303 will be oscillated thereby. The arm 306 upon which the pawl 303 is carried has a portion which is substantially concentric with the axis of the rock bar so that the bracket 305 may be adjusted along the arm 306 without changing the relative position of the ratchet and pawl. It will be readily apparent that when the rock bar 60 is oscillated in a clockwise direction, the pawl 303 rides idly over the teeth of the ratchet wheel 301 and similarly, when the bar 60 oscillates in a counter-clockwise direction, the pawl 303 engaging teeth on the ratchet wheel 301 will cause the ratchet wheel 301 to rotate a partial turn. The extent of movement of the ratchet wheel 301 or the number of teeth picked by the pawl 303 depends upon the adjustment of the bracket 305 on the arm 306. When the arm 306 rocks in a counter-clockwise direction (Fig. 12), the pawl 303 on its downward movement swings out of engagement with the ratchet wheel and on its upward movement swings into engagement and rides idly over one or more teeth of the ratchet wheel 301 which are picked to rotate the ratchet wheel 301 on

the next stroke thereof. A holding pawl 309 is pivotally mounted on a stud 310 supported by the casing 300. A tension spring 311 is connected between the upper end of the holding pawl 309 and a stud fixed to the casing 300 and serves normally to hold the holding pawl 309 in engagement with the ratchet wheel 301.

The ratchet wheel 301 is provided with an integral sleeve 312 which rotatably supports a cam 313. The cam 313 is arranged to engage an actuating roller 314 of a normally closed limit switch 315. It will be readily apparent from the foregoing disclosure that each time the rock bar 60 is rocked or oscillated by the master cam 66 and the follower roller 68, the pawl 303 will pick a predetermined number of teeth on the ratchet wheel 301 to cause an intermittent incremental rotation of the cam 313. Each oscillation of the rock bar 60 represents one complete rotation of the master cam and the product being ground. After a predetermined number of rotations of the camshaft 65 or master cam 66 or oscillations of the rock bar 60, the pawl 303 and ratchet wheel 301 will rotate the cam 313 a sufficient distance to actuate the limit switch 315 and break a circuit, thereby deenergizing the solenoid 217 which releases the compression of the spring 216 to shift the feed control-cycle pilot valve 200 and cause a separating movement between the camshaft 65 and the wheel 27 due to the operation of the vane type feed motor 172.

The cam 313 is provided with an integral sleeve having a flanged portion 316. The sleeve closely fits on the sleeve 312 and is split at one side by a saw cut 317 and is arranged to be clamped in adjusted position on the sleeve 312 by means of a screw 318. A knob 319 is fixedly pinned to the end of the shaft 302. The knob 319 is provided with a flanged portion 320 which is graduated and serves with a zero point on the flanged member 316 to facilitate adjustment of the cam member 313 relative to the pawl and ratchet mechanism.

It is desirable to provide a suitable mechanism for automatically returning the counting mechanism 300 to its initial position when the holding pawl 309 is withdrawn from the ratchet wheel 301 after a grinding cycle has been completed. A helical spring 321 surrounds an integral hub portion 322 of the casing 300. One end of the spring 321 is fastened to the hub portion 322 by means of a screw 323. The other end of the spring 321 is fixedly secured to a flanged member 324 formed integral with the shaft 302 by means of a screw 325. The spring 321 is arranged so that when the pawl 303 and ratchet wheel 301 incrementally index the cam 313, the spring 321 will be gradually wound up so that after a cam blank has been ground and the holding pawl 309 withdrawn from the ratchet wheel 301, the released tension of the spring 321 automatically turns the shaft 302, the cam 313, and the ratchet wheel 301 in a reverse direction to its initial position ready for the next grinding cycle.

It will be readily apparent from the foregoing disclosure that by adjusting the position of the cam 313 relative to the ratchet wheel 301 and relative to the roller 314 of the limit switch 315, the duration of the grinding cycle may be readily timed so that the cam blank on the camshaft being ground will rotate through a predetermined number of rotations or the rock bar will rock a predetermined number of times, after which the counting mechanism above described serves to

reverse the feed motor and automatically to control the valve mechanisms of the machine so as to index or traverse the work table to position the next cam to be ground in operative relation with the grinding wheel.

The actuation of the holding pawl 309 is preferably automatically controlled in timed relation with the other mechanisms of the machine. A fluid pressure operated cylinder 328 is fixedly mounted relative to the casing 300. A piston 329 is slidably mounted within the cylinder 328 and is provided with a piston rod 330 which is connected to actuate the holding pawl in a counterclockwise direction to move it to an inoperative position. A spring 331 within the cylinder 328 normally holds the piston in its left-hand position (Fig. 12) to hold the pawl 309 out of engagement with the ratchet wheel. When fluid under pressure is admitted to the cylinder chamber 332, as will be hereinafter described, the piston 329 and piston rod 330 are moved toward the right and the released tension of the spring 331 serves to rock the holding pawl 309 in a clockwise direction to engage the ratchet wheel 301. The timing or counting mechanism is automatically reset. When the fluid within the cylinder chamber 332 is exhausted, the released compression of the spring 331 serves to disengage the holding pawl 309 and the released tension of the spring 321 returns the counting mechanism to its initial position. This mechanism is preferably automatically controlled in timed relation with the control lever mechanism.

Control lever mechanism

The table 21 is traversed or indexed longitudinally and automatically by means of the fluid pressure system above described. It will be readily apparent from this disclosure that when the table reversing or control valve 121 is shifted from one extreme position to the other, fluid under pressure is admitted first to one end of the cylinder and then to the other. In the cycle of operation for which this improved machine is adjusted, the machine grinds successive cams on a camshaft from the footstock end of the table toward the headstock, that is, while the table 21 is intermittently indexed toward the right. When the table reaches the extreme right-hand position, the table control or reverse valve 121 is shifted into a reverse position so as to admit fluid under pressure through the pipe 119 rapidly to traverse the table toward the left to return it to its initial starting position.

The intermittent traversing of the table is accomplished by opening the table control or reverse valve 121 by moving the valve into the position shown in Fig. 3, whereupon the table is traversed until a lever is engaged to shift the valve 121 to a central position to cut off fluid under pressure from both ends of the table cylinder, thereby stopping the table in position to grind the next cam blank on the camshaft 65. An actuating mechanism is provided for the valve 121 so that movement of the table 21 operates to close the valve 121 so that when the table is traversed through a predetermined distance to position the next cam on the camshaft 65 being ground in operative relation with the grinding wheel 21, the valve 121 is automatically shifted to a central or neutral position to stop the flow of fluid under pressure to either end of the table cylinder 110. This is preferably accomplished by means of a dog bar 330a which is adjustably mounted on the front edge of the table 21 by

means of bolts and a T-slot (Fig. 5). The dog bar 330a is provided with elongated slots 331a (Fig. 4) which serve adjustably to support a plurality of adjustable dogs 332a. The dogs 332a may be adjusted along the bar to conform with the spacing of the cams on the camshaft 65 to be ground. The dog bar, if necessary for any variation in successive camshafts, may be adjusted longitudinally of the table without upsetting the adjustment of the individual dogs.

The valve 121 is provided with a valve stem 122 which is operatively connected to a manually operable control lever 333 which is supported on the forward end of a rock shaft 334. In the preferred form, the lever 333 is pivotally supported on a stud 335 which is carried by a short lever 336 which is rigidly secured to the front end of the rock shaft 334. The inner end of the rock shaft 334 carries fixedly mounted thereon a downwardly extending lever 337 which is provided with a follower member 338 which in turn engages a groove in a spool-shaped member 339 mounted on the end of the valve stem 122 so that by manually rocking the lever 333, the table control valve 121 may be readily shifted to change the direction of movement of the table 21. In order that the control lever 333 may be moved in the direction of table movement, a second actuating lever is provided for cooperating with the table dogs. As illustrated in the drawings, a dog lever 340 is provided with a forwardly projecting pin or stud 342 which rides in a rectangularly shaped aperture 343 within the short lever 336. The extent of movement of the lever 340, without transmitting motion to the main control lever 333, is controlled by the adjustment of a pair of spaced opposed screws 344 and 345 which are arranged on opposite sides of the rectangularly shaped aperture 343.

The lower end of the lever 337 is provided with a cam plate having a portion 346 which is substantially concentric with the axis of the rock shaft 334 and an angularly arranged cam surface 347 arranged at approximately 45°. A roller 348 carried by a spring-pressed plunger 349 serves normally to hold the lever 337 in its extreme left-hand position, that is, with the table control valve 121 in the position illustrated in Fig. 3.

Assuming the table 21 to be traveling in the direction of the arrow (Fig. 4), this movement continues until the table dog 332a engages the dog lever 340 and rocks the lever in a clockwise direction until the stud or screw 344 is engaged by the stud 342, and further movement rocks the control lever 333 in a counterclockwise direction, which serves to rock the lever 337 into substantially the position shown in Fig. 4, which movement shifts the valve stem 122 slightly toward the right (Fig. 3) so that fluid under pressure is cut off from both the pipe 119 and the pipe 120, thus stopping the table 21 in the desired position for grinding the next cam on the camshaft.

The dog lever 340 is pivotally supported on the stud 341 and is arranged to swing in a direction parallel with the table movement. The dog lever 340 is provided with an integral hub portion 350 which is arranged so that it may be moved longitudinally on the pin or stud 341 so as to throw the dog lever 340 out of the path of the table dogs 332a. In the preferred form a mechanism is provided for automatically throwing the dog lever 340 out of engagement with the table dog 332a in timed relation with the other movements of the table. A rock arm 351 is pivotally

supported on a stud 352 which is fixed relative to the base of the machine. The upper end of the lever 351 is formed as a yoke-shaped member having a pair of diametrically opposed pins 354 and 355 which engage apertures within the sleeve 356 so that when the lever 351 is rocked in a clockwise direction about its supporting stud 352, the hub 350 will be moved toward the right (Fig. 5) and the dog lever 340 will be moved out of the path of the table stop dog 332a, which serves to release the spring-pressed plunger 349, and the roller 348 rocks the cam 347 and the lever 337 in a clockwise direction (Figs. 3 and 4) to move the valve 121 into the position illustrated in Fig. 3 so that the pipe 120 is uncovered to allow passage of fluid to the cylinder chamber 113. It is desirable that the dog lever 340 be thrown out of engagement with the table stop dogs 332a in timed relation with the other parts of the machine. This is preferably accomplished by means of a fluid pressure actuated mechanism comprising a cylinder 360 having a piston 361 slidably mounted therein. A piston rod 362 is connected to move with the piston 361 and an adjustable screw 363 carried in the forward end of the piston rod 362 is arranged to engage the lower end of the lever 351. A spring 364 normally holds the piston 361 in a right-hand position (Fig. 5) so that the stop lever 340 is in the path of the table stop dogs 332a. A spring 365 (Fig. 4) which is interposed between a projecting lug 366 on the lever 351 and a portion of the base 21 serves to hold the lever 351 in the position shown in Fig. 5. When fluid under pressure is admitted through a pipe 367 into a cylinder chamber 368, the spring 364 is compressed and the lever 351 rocked in a clockwise direction (Fig. 5) to move the dog lever 340 toward the right out of the path of the table dogs 332a. The pipe 367 is connected with the valve chamber 253 of the main control valve 220 so that in the position of the main control valve shown in Fig. 3, fluid will be admitted to remove the table stop lever 340 from the path of the table dogs 332a. The cycle control mechanism 300 above described is operative only during the infeeding or grinding cycle and is preferably arranged so that it is automatically rendered inoperative during the table traversing movement. This is preferably accomplished by providing a control valve which is actuated by movement of the table control lever so as to control the admission of fluid to a cylinder 330. In the preferred form of this invention, the spring-pressed plunger 349 is formed as a control valve for the cycle control mechanism. The plunger 349 is slidably mounted within a casing or cylinder 370 which is supported on the rock shaft 334. An upwardly extending lug 371 is held between two opposed adjusting screws 372 (only one of which has been shown in Fig. 5). The opposed adjusting screws 372 serve to adjust the position of the cylinder or casing 370 so that the valve and the roller 348 may be adjusted relative to the cam surface 347 in setting up the mechanism. The plunger 349 is provided with a pair of valve pistons 373 and 374 having a valve chamber 375 therebetween. Fluid under pressure from the pump 207 passes through a pipe 376, and in the position of the parts as shown in Fig. 3, fluid under pressure passing through the pipe 376 is blocked by the piston 374. A pipe 377 which is connected between the cylinder chamber 332 and the valve chamber 375 (Fig. 3) is connected with an exhaust pipe 378 which serves to allow

the fluid within the cylinder chamber 332 to exhaust and thereby release the tension of the spring 341 (Fig. 12) which rocks the holding pawl 309 into an operative position in engagement with the ratchet 301 to start actuation of the cycle control mechanism.

When the valve 121 is thrown into a reverse position or is shifted to stop the table movement, the roller 348 actuated by the cam surface 347 causes the spring-pressed plunger 349 to move upwardly, thus admitting fluid under pressure from the pipe 376 through the pipe 377 to the cylinder chamber 332 to hold the holding pawl 309 out of engagement with the ratchet wheel. Before the holding pawl 309 is withdrawn, the cam 313 has rotated a sufficient distance to open the limit switch 315 which serves to break the circuit, thereby deenergizing the solenoid 217, and the released compression of the spring 216 shifts the control valve 200 toward the right (Fig. 20) which in turn shifts the main control valve.

In the position of the parts shown in Fig. 3, when the dog lever 340 is thrown out of the path of the table stop dogs 332a, the table 21 does not move due to the fact that the piston 222 of the main control valve 220 covers the port at the end of the pipe 254 (Fig. 3) so that no fluid under pressure can pass through the pipe 127 to the table control valve 121 during the grinding feed. This condition continues until the cycle control or feed control valve 200 shifts into a reverse position to start the table movement.

An adjustable stop screw 380 carried by the lever 333 serves to limit the rocking movement of the main control lever 333 in a counterclockwise direction (Fig. 5). The compression of the spring 365 (Fig. 4) serves normally to hold the lever 333 in a substantially vertical position with its lower end against the stop screw 380. The lever 333 is provided with an inwardly projecting lug 381 which is arranged in the path of the hub 350 of the dog lever 340 so as to facilitate manually throwing the dog lever 340 out of the path of the table dogs 332a to start the operating cycle of the machine.

Wheel spindle reciprocation

In the preferred construction, the grinding wheel 24 and its supporting spindle 26 are reciprocated axially through a short distance during the grinding operation so as to cause an even wearing of the grinding wheel face during grinding and to improve the quality of the finish produced on the cam being ground by preventing grain markings or rings around the cam being ground. The wheel spindle reciprocating mechanism has not been illustrated in detail, since this is not considered a part of the present invention. A wheel spindle reciprocating mechanism is contained within a portion 382 of the wheel 24 slide casing. Reference may be had to the prior U. S. patent to Belden and Silven No. 2,022,178 for details of disclosure not contained herein. It is desirable that the wheel spindle reciprocating mechanism be stopped during the truing of the grinding wheel 24 in order that a better finish may be obtained on the grinding face of the wheel. It is also desirable that the wheel reciprocation be automatically stopped in timed relation with the other mechanisms of the machine so that when the truing tool is moved into operative engagement with the wheel, the wheel will be held against reciprocatory movement. A pipe 383 passes fluid under pressure to a valve chamber 384 located between the valve pistons 373 and 374.

263 and 264 in the slow speed valve 260. When the slow speed valve 260 is shifted toward the right (Fig. 3) to slow down the table movement for a truing operation, fluid under pressure within the valve chamber 384 passes out through a pipe 385 to the wheel spindle reciprocating mechanism contained within the casing 382 automatically to stop the reciprocation of the spindle. After the truing operation has been completed, the slow speed valve 260 shifts back to the position shown in Fig. 3 and fluid may exhaust through the pipe 385 and a valve chamber 386 located between the valve pistons 264 and 265 and out through a pipe 387 which returns fluid to the reservoir 206, thus allowing the wheel spindle 26 reciprocating mechanism to start functioning and reciprocate the wheel spindle 26 for a grinding operation.

In traversing from cam to cam as well as stopping at the end of the table stroke, it is desirable that the counting mechanism be rendered inoperative and that the solenoid 217 be deenergized so that the rock bar 60 will remain in an inoperative position to hold the cams on the cam-shaft 65 out of engagement with the wheel 27 when the table traverses over a comparatively long section of the shaft, such as the center bearing, and furthermore to retain the cam-shaft separated from the grinding wheel during the truing operation. A normally closed limit switch 390 is mounted on the front of the machine base and is connected in series with the limit switch 315 of the cycle control mechanism. A plurality of dogs 391 are arranged in fixed positions on the dog bar and serve to open the limit switch 390 at the desired intervals during the intermittent indexing of the table 21. Opening the switch 390 serves to open the circuit of the limit switch 315, thus deenergizing the solenoid of a relay switch 392 which serves to deenergize the solenoid 217, and the released compression of the spring 216 retains the feed control-cycle pilot valve in its right-hand position (Fig. 3) to retain the feed motor 172 and the cam-shaft 65 in a rearmost position and prevent the cam-shaft 65 from moving forward into engagement with the grinding wheel 27 at times when the table is traversing over a main bearing or during the truing operation. A normally closed limit switch 394 is connected to a relay switch 395 and serves to stop the work drive motor 134 during the truing operation. A dog 396 carried by the table 21 serves to open the limit switch 394 and thereby stop the work drive motor 133.

A lever 397 is pivotally mounted on a stud 398 which is fixed to the base. An adjustably positioned stud 399 carried at the left-hand end of the lever 397 (Fig. 4) is arranged in the path of the dogs 391 and serves when engaged by the dogs 391 to rock the lever 397 in a counterclockwise direction so that the adjustable screw 400 engages an actuating roller 401 of the limit switch 396 to open the switch. The rock arm 397 is also provided with a cam surface 402 at its other end which is arranged to be engaged by a stud 403 carried by the main control lever 333 to facilitate manual operation of the switch 396 when the main control lever is shifted to start the cycle of operation.

Operation

The operation of this automatic cam grinding machine is readily apparent from the foregoing disclosure. Assuming the table 21 has stopped

after the truing operation has been completed, the dog lever 340 engages the right-hand side of the table stop dog 405, which shifts the control valve 121 toward the right (Fig. 3) to hold the table 21 stationary during a loading operation. A new camshaft is mounted in position and supported for rotation on the headstock spindle 62 and footstock center 64. Assuming all of the parts to have been previously adjusted, the cycle of operation is started by movement of the main control lever 333 in a clockwise direction (Fig. 5) which serves to throw the dog lever 340 out of the path of the table stop dog 405. The released compression of the spring back of the plunger 349, acting through the roller 348 and the cam face 367, serves to rock the lever 337 in a clockwise direction (Fig. 3) which shifts the table control valve 121 into the position illustrated in Fig. 3 so that fluid under pressure is admitted into the cylinder chamber 118. In this position of the parts, the valve 200 is in its extreme right-hand position (Fig. 3) which serves to shift the main control valve 220 into its extreme left-hand position, thus allowing fluid under pressure to flow through the pipe 254, the pipe 127, into the valve chamber 128 in the table control valve 121 and through the pipe 120, into the cylinder chamber 118, to cause the table 21 to move toward the right (Figs. 1 and 3). When the main control valve 220 shifts into its left-hand position, the pipe 367 is opened to the exhaust and the released compression of the spring 364 shifts the piston 361 toward the right (Figs. 3 and 5) to release the compression of the spring 365 which rocks the lever 337 in a counterclockwise direction (Fig. 5) to shift the dog lever 340 into the position illustrated in Fig. 5 in the path of the table stop dogs 332a. When the dog lever 340 engages the first table stop dog 332a, the lever 340 is rocked in a clockwise direction (Fig. 4) until the stud 342 engages the screw 346 to rock the lever 336 and main control lever 333 so as to rock the shaft 334 in a counterclockwise direction and the lever 337 in a counterclockwise direction (Fig. 4) so as to shift the table control valve 121 toward the right (Fig. 3) to cut off fluid under pressure from both ends of the table cylinder 110.

During the shifting movement of the lever 337 in a counterclockwise direction, the cam 347 forces the roller 348 upward against the compression of the spring contained within the plunger 349 which serves to shift the valve piston 374 so as to uncover the port at the end of the pressure pipe line 376 to admit fluid under pressure to the valve chamber 375 which is also connected with the pipe line 377 to pass fluid under pressure to the cylinder within the casing 329 to rock the holding pawl 307 from operative engagement with the ratchet wheel 301, thereby releasing the tension of the spring 321, which resets the counting mechanism and returns the limit switch 315 to a closed position so as to close a circuit, thereby energizing the solenoid 217 to shift the feed control-cycle pilot valve 200 into the position illustrated in Fig. 3. In this position, the main control valve 220 is shifted toward the right which serves to pass fluid under pressure from the pipe 252 through the valve chamber 253 and the pipe 367 into the cylinder chamber 368 which serves through the lever 337 to rock the dog lever 340 out of the path of the table dogs 332a. At the same time, fluid under pressure is passed from the feed control or cycle pilot valve chamber 211 through the pipe 95 into the rock bar 75

5 cylinder chamber 94 to swing the rock bar and move the master cam 66 into operative engagement with the master cam follower roller 68. Also, at the same time, fluid passes through the 10 pipe 212 and passage 176 to start the counter-clockwise rotation of the vane 174 in the feed motor 172 which serves to rotate the shaft 175 which in turn oscillates the eccentric portion 89 bodily to move the master cam roller 68 so as to 15 feed the cam being ground relatively toward the operative face of the grinding wheel 27 to facilitate grinding a cam to the predetermined size. The vane 174 makes one-half rotation during this infeeding movement and at each oscillation of the 20 rock bar 60, the ratchet wheel 301 is intermittently actuated to rotate the cam 313 so that after a predetermined number of oscillations of the rock bar 60 or rotations of the camshaft 65, the cam 313, through the roller 314, will open 25 the limit switch 315 which operates through the relay switch 392 to deenergize the solenoid 217 whereby the released compression of the spring 216 shifts the feed control or cycle pilot valve 200 toward the right which serves again to shift 30 the main control valve 220 toward the left (Fig. 3) to allow the dog lever 340 to shift back into the path of the table dogs 332a. Also, to reverse the flow of fluid to the feed motor 172 which rocks the eccentric shaft 69 to separate the cam 65 being 35 ground from the operative face of the grinding wheel 27 and at the same time admit fluid under pressure to the rock bar cylinder chamber 93 to rock the bar 60 to an inoperative position, thereby separating the master cam 66 from the 40 follower roller 68. At the same time the main control valve 220 moves toward the left (Fig. 3), fluid under pressure is admitted through the pipes 254 and 127 to the table control valve 121, which is in the position illustrated in Fig. 3, to 45 cause the next table indexing movement toward the right to position the next cam blank in operative relation with the grinding wheel 27. Each time the table 21 is indexed to position a new cam to be ground in operative relation with 50 the grinding wheel 27, the master cam roller 68 is automatically indexed in timed relation with the table movement by the mechanism shown in Fig. 11 to position the master cam roller 68 in operative relation with the master cam 66 which corresponds with the cam to be ground.

55 This cycle of operation is continued until all of the cams on the camshaft 65 have been ground and a table reverse dog 410 engages the pilot valve lever 242 to rock it in a clockwise direction (Fig. 3) which serves to admit fluid under pressure from the pipe 243 into the pipe 245 which conveys fluid under pressure to the valve chamber 246 at the left-hand end of the table control valve 121 which serves to shift the table control 60 valve stem 122 toward the right (Fig. 3). This movement reverses the direction of flow of fluid under pressure to the cylinder 110 to move rapidly toward the left the table 21. During this movement, the lever 337 is shifted in a clockwise 65 direction and the roller 348 is raised to ride upon the concentric surface 346 so as to hold the valve pistons 373 and 374 in the position illustrated in Fig. 4 with fluid under pressure applied to the cycle control mechanism cylinder to hold the 70 holding pawl 309 in an inoperative position and to return the parts of the cycle control mechanism to their initial position ready for the next grinding cycle. The table 21 traverses at a comparatively rapid rate toward the left in its idle 75 stroke toward its initial starting position. This

rapid return movement of the table 21 toward the left (Figs. 3 and 4) continues until after the table stop dog 405 rides idly over the dog lever 340 whereupon the cam surface 275 engages the roller 273 to shift the slow speed valve 250 to throttle the exhaust of fluid from the table cylinder 110 so as to slow down the traversing speed of the table 21 to a slow predetermined truing speed as the truing tool 259 is moved into engagement with the face of the wheel 27. The movement 10 of the table 21 toward the left continues until an adjustable dog 406 on the truing dog 276 engages the lever 242 and rocks it in a counterclockwise direction to shift the pilot valve 230 in the opposite direction. Fluid under pressure passing 15 through the pipe 248 enters the pipe 121 to shift the reverse or table control valve 121 into the position illustrated in Fig. 3. The table 21 then starts its traversing movement toward the right while the diamond or truing tool 259 is passed a 20 second time across the periphery of the grinding wheel 27. Before the diamond 259 engages the wheel on its first pass, a table dog operates the pawl and ratchet nut and screw mechanism to advance the grinding wheel by an amount it 25 is desired to true off the wheel so that a fresh wheel face is provided which is in a definite relationship with the final feeding position of the cam to be ground. The table 21 continues its movement toward the right until the table stop 30 dog 405 engages the dog lever 340 which shifts the table control valve 121 to cut off fluid under pressure from either end of the table cylinder to stop the table movement with the table and parts in a loading position. The ground cam-shaft may then be removed from the machine and a new shaft to be ground inserted thereinstead.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. A cam grinding machine having a rotatable grinding wheel, a rock bar, a rotatable camshaft thereon, means including a master cam and a rotatable follower roller to rock said bar to grind a predetermined contour on a cam blank, a rotatable eccentrically mounted shaft to support said follower roller, means including a fluid motor to oscillate said shaft so as to cause a relative approaching movement between the axes of said roller and grinding wheel, a cam which is rotated by said fluid motor, a follower actuated by said cam, and adjustable lever connections actuated by said follower to rotate said eccentric shaft whereby the extent of infeed may be varied as desired.

2. A cam grinding machine having a rotatable grinding wheel, a rock bar, a rotatable camshaft support thereon, means including a master cam and a rotatable follower roller to rock said bar to grind a predetermined contour on a cam blank, a rotatable eccentrically mounted shaft to support said follower roller, and means including a fluid motor to oscillate said shaft so as to bodily move the follower roller during the grinding operation to cause a grinding feed and grind the cam blank to a predetermined size.

3. A cam grinding machine having a rotatable grinding wheel, a rock bar, a rotatable camshaft support thereon, means including a master cam and a rotatable follower roller which are arranged to rock said bar to grind a predetermined contour on a cam blank, a rotatable eccentrically mounted shaft to support said roller, means including a fluid motor to oscillate said shaft to bodily move said roller during the grinding operation so as to cause a grinding feed to grind the cam blank to a predetermined size, and adjustable connections between said motor and eccentric shaft whereby the extent of infeed may be varied.

4. A cam grinding machine having a rotatable grinding wheel, a rock bar, a rotatable camshaft support thereon to support a camshaft having a plurality of cam blanks formed integrally therewith, means including a master cam and a follower roller to rock said bar to grind a predetermined contour on a cam blank, a rotatable eccentrically mounted shaft to support said roller, means including a single vane type fluid motor operatively connected to oscillate said shaft to bodily move said roller during the grinding operation to cause a grinding feed to grind the cam blank to a predetermined size, and means including an adjustable valve to regulate the speed of said motor in at least one direction so as to control the rate of infeeding movement.

5. A cam grinding machine having a rotatable grinding wheel, a rock bar, a rotatable camshaft support thereon rotatably to support a camshaft having a plurality of cam blanks formed integrally therewith, means including a master cam and a rotatable follower roller to rock said bar to grind a predetermined contour on a cam blank, a rotatable eccentrically mounted shaft to support said roller, means including a single vane type fluid motor which is operatively connected to oscillate said shaft and bodily to move said roller toward the wheel axis so as to grind a cam blank to a predetermined size, an adjustable valve associated with said motor which serves to regulate the speed of said motor in at least one direction to control the rate of infeeding, and adjustable connections between said motor and eccentric shaft whereby the extent of infeeding may be varied.

6. In an automatic cam grinding machine having a rock bar, a cycle timing device including a pawl and ratchet mechanism, a pawl carrying arm on said bar which is arranged to actuate said pawl each time said bar is rocked, a safety or holding pawl, yieldable means to maintain said pawl in engagement with said ratchet wheel during a grinding cycle, a fluid pressure operated piston and cylinder to disengage said holding pawl, a pivotally supported control valve therefor, means including a cam to actuate said valve so as to render the cycle timing device inoperative, and means relatively to adjust the position of the control valve about its pivotal support so as to vary the position of the valve relative to the cam.

7. In an automatic cam grinding machine having a transversely movable rotatable grinding wheel, a longitudinally movable table, a rock bar on said table, a rotatable camshaft support on said bar, means including a plurality of master cams on said bar arranged in axial alignment with said camshaft support, a follower associated therewith to rock said bar so as to control the contour and size of the cam being ground, a table indexing mechanism including a control lever automatically to index said table to position a plurality of cams successively into operative rela-

tion with said grinding wheel, a cycle timing device including a pawl and ratchet wheel actuated by said rock bar, a fluid pressure piston and cylinder to render said device inoperative, an adjustably mounted control valve therefor, means to adjust the position of said control valve, and a cam actuated by said lever to actuate the control valve.

8. In an automatic cam grinding machine having a transversely movable rotatable grinding wheel, a longitudinally movable table, a rock bar on said table, a rotatable camshaft support on said bar, means including a plurality of master cams on said bar in axial alignment with said camshaft support, a rotatable follower operatively associated therewith to rock said bar so as to cause a relative transverse approaching and receding movement between the camshaft support and the grinding wheel to control the contour and size of the cam being ground, a table indexing mechanism including a control lever automatically to index said table to position a plurality of cams successively into operative relation with said grinding wheel, a cycle timing device including a pawl and ratchet wheel actuated by said rock bar, a fluid pressure piston and cylinder to render said device inoperative, a control valve therefor, and means actuated by and in timed relation with movement of the control lever to actuate said control valve.

9. In an automatic cam grinding machine having a transversely movable rotatable grinding wheel, a longitudinally movable table, a rock bar on said table, a rotatable camshaft support on said bar, means including a plurality of master cams and a follower to rock said bar so as to control and size the cam being ground, a table indexing mechanism including a control lever automatically to index said table to position a plurality of cam blanks successively into operative relation with said grinding wheel, a cycle timing device including a pawl and ratchet actuated by said rock bar, a fluid pressure piston and cylinder to render said device inoperative, a control valve therefor, and means actuated by said lever to operate the control valve.

10. In an automatic cam grinding machine having a rock bar, a cycle timing device including a pawl and ratchet wheel mechanism, a pawl carrying arm on said bar, a safety or holding pawl, yieldable means to maintain said holding pawl in engagement with said ratchet wheel during a grinding cycle, a fluid pressure operated piston and cylinder to disengage said holding pawl, a control valve therefor, and means including a cam to actuate said valve to render said cycle timing device inoperative.

11. In a cam grinding machine, a rotatable grinding wheel and a work support for rotatably supporting a camshaft which are movable longitudinally and transversely relative to each other, means to cause a predetermined transverse movement of the work support toward and from the grinding wheel to grind a cam blank to a predetermined contour and size, means including a piston and cylinder to cause an intermittent relative longitudinal indexing movement between the grinding wheel and the work support in one direction to position successive cams in operative relation with the grinding wheel for grinding, a valve to control the flow of fluid to and from said cylinder, and means including an adjustable stop to limit the movement of said valve in one direction to adjust the speed of said indexing movement, said valve being arranged to allow

free exhaust of fluid from said cylinder when the valve is shifted in the reverse direction to cause a rapid longitudinal traversing movement between the wheel and work in the opposite direction quickly to return the same to the initial position.

12. In a cam grinding machine, a rotatable grinding wheel and a work support for rotatably supporting a camshaft which are movable longitudinally and transversely relative to each other, means to cause a predetermined transverse movement of the work support toward and from the grinding wheel to grind a cam blank to a predetermined size and contour, means to cause an intermittent longitudinal indexing movement between the grinding wheel and the work support in one direction to position successive cams in operative relation with the grinding wheel for grinding, means to adjust the speed of said indexing movement, means to cause a rapid relative longitudinal traversing movement between the wheel and work in the opposite direction rapidly to return the same to the initial position, a truing tool carried by the work support, and means including independently adjustable valves to cause said truing tool to pass across the face of the wheel in each direction at independently adjustable speeds and then to stop in a loading position.
13. A cam grinding machine having a rotatable grinding wheel, a rock bar, a rotatable camshaft thereon, means including a master cam and a

rotatable follower roller to rock said bar to grind a predetermined contour on a cam blank, a rotatable eccentrically mounted shaft to support said follower roller, and means including a fluid motor to oscillate said shaft so as to cause a relative approaching and receding movement between the axes of the roller and grinding wheel.

14. A cam grinding machine having a rotatable grinding wheel, a rock bar, a rotatable camshaft thereon, means including a master cam and a rotatable follower roller to rock said bar to grind a predetermined contour on a cam blank, a rotatable eccentrically mounted shaft to support said follower roller, and means including a vane type fluid motor to oscillate said shaft so as to impart a secondary motion to the work carriage and thereby cause the work to feed into the wheel.

15. In a cam grinding machine having a rock bar, an actuating mechanism therefor including a piston and a cylinder which are operatively connected to actuate said rock bar, yieldable means including a compression spring interposed between said piston and cylinder and rock bar, an adjustable stop to limit the movement of the rock bar when it is moved to an inoperative position, and readily accessible means to adjust the compression of said spring, said yieldable means being arranged so that it is under compression only when the rock bar is moved to an operative position.

HERBERT A. SILVEN.

30
